EXHAUST HEADER FOR AUTOMOBILES

Kenneth Maynard and Paul E. Hansen, Los Angeles, Calif.

Application August 23, 1954, Serial No. 31,972

Term of patent 14 years

(Cl. D14—6)

Figure 1 is a perspective view of an exhaust header for automobiles embodying our new design.

Figure 2 is another perspective view thereof.

Figure 3 is a side view thereof.

Figure 4 is a bottom view thereof.

Figure 5 is a top view thereof.

Figure 6 is an end view taken as from the left-hand end of Figure 5.

We claim:

The ornamental design for an exhaust header for automobiles, substantially as shown.
